FACSIMILE TELEGRAPH SYSTEM

Edward Fisk Watson, Larchmont, N. Y., assignor
to American Telephone and Telegraph Company, a corporation of New York

Application September 26, 1933, Serial No. 691,044

7 Claims. (Cl. 178—5)

The present invention relates to telegraph systems in which each letter or symbol to be transmitted is scanned or analyzed into a succession of constituent elemental or unit areas of positive and negative surfaces. The positive or negative nature of each such elemental or unit area is then communicated by a telegraphic signal from the sender to the receiver, where it is recorded upon a suitable receiving surface such as a paper 5 tape, for example, according to the nature of the signal, and in directly intelligible form such as lines which constitute letters and/or figures.

An object of this invention is to reduce the width of the band of frequencies necessary to 10 transmit individual lines of letters and figures when the letters occupy one horizontal line and the figures occupy another horizontal line which runs parallel with the first line, but is spaced or "offset" therefrom.

20 A further object is to reduce the speed of response required of the recording device and the work which it is required to do.

The receiver includes a printing wheel which is provided on its circumferential surface with 25 symmetrical spiral edges which are adapted to print or record letters and figures upon a receiving tape when said tape is being pressed upon the edges by a platen number which has the form of a knife edge and which is driven toward 30 the paper tape in accordance with the current fluctuations flowing through a movable coil integral with the platen member.

This type of receiving unit is particularly 35 adapted to receive broadcast messages such as news bulletins and stock quotations. In the recording of stock quotations it is customary to print or record the symbols identifying the issues involved in a transaction on a horizontal row, whereas the price or quotation of the issue is 40 printed or recorded on a row parallel thereto, usually "offset" or below to the right of the letter symbols. Although this printing receiver is particularly well adapted to receive stock quotations, for such a printer to print stock quotations 45 on a receiving tape with the letters and figures offset from each other requires a considerably wider range of frequencies than would be the case if the letters and figures were printed in the same row. If the offset is to be 100% then the 50 range of frequencies required for transmitting letters and figures would be twice the frequency range required for transmitting a single row of letters and/or figures.

In accordance with the present invention, letters and figures may be printed on a receiving

tape with a 100% offset without its being necessary to transmit a range of frequencies wider than that required for one row of printed matter. This is accomplished by the provision of two platen members instead of one, one platen being 5 designed for reproducing characters in one line and the other for reproducing characters in the second or offset line, the edges of these platen members being in a line and operating against a widened printing wheel. Two transmitters are 10 required at the transmitting station, one for sending the characters of one line and the other for sending the characters of the other line. One of the transmitters is so connected into the circuit as to apply positive impulses to the line, and 15 the other so as to apply negative impulses to the line. At the receiving station, the moving coil operated by the transmitted current which operates one of the platen members is designed to respond to positive impulses, and the moving coil 20 operating the other platen is designed to respond to negative impulses. In this manner one of the moving coil units will reproduce the characters in one horizontal row, while the other moving coil unit will reproduce characters in a horizontal row parallel to said first row, and the 25 width of the range of frequencies required is thus considerably reduced.

The invention may be more fully understood from the following description when read with 30 reference to the attached drawing of which:

Figure 1 shows a schematic drawing of the system;

Fig. 2 shows a perspective view of the receiving apparatus;

Fig. 3 shows a side and partial sectional view of the receiving apparatus;

Fig. 4 shows a portion of the tape with symbols recorded thereon; and

Fig. 5 shows the details of a typical transmitting cam for generating current impulses representing the symbols to be transmitted.

Referring now to Fig. 1, S represents the sending station connected to a receiving station R by the telegraph line 1. The transmitter at the sending station S has two sets of transmitting cams 3 and 4 mounted on shaft 2. Shaft 2 is rotated by a motor through suitable gearing and clutches which are not shown since they form no part of the present invention. Cams 3 are connected to 45 positive battery 9 through brushes 11, switches 5 and resistance 7. In a similar manner cams 4 are connected to negative battery 10 through brushes 12, switches 6 and resistance 8. Switches 5 and 6 represent a method of selecting the va- 50

rious cams and may be controlled in any suitable manner, such as a keyboard or tape. The cams may also be selected by other means such as friction clutches and latches or by raising and lowering the brushes associated with each cam which in turn could be controlled by a tape or a keyboard. As shown these cams are connected through shaft 2 to collector ring 13. Ring 13 is connected to line 1 by brush 14.

10 The receiving apparatus located at the receiving station R comprises a printing wheel 15, mounted on shaft 16. Shaft 16 may be continuously rotated in synchronism with shaft 2 at the sending station S or shafts 2 and 16 may be controlled by appropriate start-stop mechanisms. However, since these various methods of controlling shafts 2 and 16 form no part of the present invention, they have not been illustrated. Printing wheel 15 is provided with a plurality of spiral 15 printing edges or ridges 17. Two sharp edged platens 18 and 19 are supported adjacent this printing wheel on coils 20 and 21, respectively. These coils are supported in radial magnetic fields by spring members 22 and 23 (see Figs. 2 and 3).

20 Paper tape 24 and ink ribbon 25 are pulled between platen 18 and printing wheel 15 through suitable guides (not shown) in any convenient manner. Coils 20 and 21 are suspended in radial magnetic fields due to electromagnets 26 and 27 having windings 29 and 30 through which a current is passed by battery 28 as shown in Fig. 1. Coils 20 and 21 are connected to line 1 so that one of them moves toward printing wheel 15 when a positive impulse is applied to line 1 at the sending station S and the other coil moves toward printing wheel 15 when a negative impulse is applied to line 1 at sending station S. When coil 20 moves platen 18 towards printing wheel 15 so that the ink ribbon 25 and tape 24 are compressed between platen 18 and printing wheel 15, a mark will be made on tape 24 in one line and when platen 19 presses ink ribbon and tape 24 against printing wheel 15 marks will be made upon tape 24 in the other line. Thus by sending 25 appropriate positive impulses over line 1 from station S, one of the platen members, say platen 18, will force ink ribbon 25 and tape 24 against printing wheel 15 in accordance with said impulses and thus print the symbol represented by 30 said impulses on the right half of tape 24 as seen in Fig. 1. In a similar manner negative impulses will cause the symbol which they represent to be printed on the left half of tape 24.

35 The manner in which the impulses are sent which represent various symbols to be recorded will now be described with reference to Figs. 4 and 5. Fig. 4 shows a section of tape with the letter A recorded in the upper row and the numerals 95 in the lower row. As shown, the space 35 allotted to each symbol is divided up into small unit areas of which there are sixteen along the tape and eighteen across the tape allotted to each symbol to be transmitted. An impulse is transmitted representing each space if that space is to be darkened or printed in and no impulse is transmitted if there is to be no mark in that space. Time is allotted to transmit the impulses representing these spaces starting with space 32 across the tape to space 33 and then from 34 across the tape to space 35, etc. Fig. 4 shows the manner in which these impulses are transmitted by a typical cam cut to transmit the letter A as printed in Fig. 4. The cam is started to rotate, brushes 11 or 12 lowered, or switches 6 and 7 closed at the point marked start 32A on

the cam in Fig. 5. As the cam rotates in a clockwise direction as viewed in Fig. 5 the brushes will pass from point 32A to point 33A, but since the cam is cut away no marking impulses will be transmitted so that spaces 32 to 33 would be blank as shown in Fig. 4. In a similar manner since cam A is cut from point 34A to point 35A, the corresponding spaces 34 to 35 on the tape in Fig. 4 will also be blank. The raised portion 36A will transmit marking impulses which will mark the receiving tape as shown at 36. Raised portion 37A will similarly transmit a series of marking impulses shown at 37 on Fig. 4. Thus by sending impulses for each space or unit area allotted to each symbol, that is to be marked the entire symbol may be transmitted.

It is also obvious that if it is desired to transmit and record symbols in two lines, each of which must be divided up into unit areas and transmitted over the line, twice as many unit areas must be represented by impulses so that it would take twice as long, or the impulses would need to be transmitted twice as fast and thus require twice the frequency band as that required to transmit and record the symbols in one line. 25 However, by employing positive impulses to cause marking in the unit areas of one line and negative impulses to cause marking in the unit areas of the other line on said tape, the symbols may be transmitted at the same speed and with the same 30 frequency band as that required to transmit and record the symbols in a single line, or the time required to transmit the signals and record them in two lines will be cut in two, or the frequency band cut in two, and thus effect a considerable 35 saving in line time.

A further advantage of this arrangement is that the platens may be smaller and lighter than a single one of double width so that they will respond more readily and faster than a single 40 platen of double width.

The above description of a specific embodiment of the invention is to illustrate rather than restrict the invention, since there may be many modifications of this specific embodiment of the 45 invention within the scope of the appended claims. For example, two separate circuits or radio channels might be employed to transmit the two groups of signals separately to the two receiving coils, or the signals might be recorded 50 directly by pressure on a wax coated paper instead of using an inking ribbon and ordinary paper.

What is claimed is:

1. In a facsimile telegraph system, means for 55 recording successive series signal impulses which represent elemental areas of symbols in any one of a plurality of rows on a single tape which comprises a plurality of receiving mechanisms each of which comprises impulse receiving means, a 60 platen member controlled thereby, and printing means for receiving and recording impulses representing symbols in the respective rows, and circuit instrumentalities connecting said mechanisms to the telegraph system for controlling said 65 mechanisms in accordance with received signal impulses.

2. A facsimile telegraph system for transmitting stock quotations which comprises a transmitting device, a group of cams connected therewith for transmitting groups of impulses representing unit areas of the stock symbols, a second group of cams connected with said transmitting device for transmitting other groups of impulses representing unit areas of the stock quotations, 70 75

a transmission line connected to said two groups of cams and extending to receiving apparatus for recording said impulses on a tape, said receiving apparatus having receiving and recording means 5 for receiving and recording the impulses representing the stock symbols in one row on said tape and having other receiving and recording means for receiving and recording impulses representing the quotation on a second row on said tape 10 which is parallel to but displaced from said first row.

3. In a facsimile telegraph receiver adapted for the reception of letter characters and figure characters, a rotating printing wheel provided 15 with a plurality of spiral printing edges, means actuated by the received current impulses for reproducing letters and figures, and an ink ribbon and a paper tape intermediate said printing wheel and said means, said means having a plurality of independently actuated platen members 20 arranged offset one from the other.

4. In a facsimile telegraph system adapted to record stock quotations, a receiver having a driven printing wheel provided with a plurality of 25 spiral printing edges, a plurality of platen members offset each from the other, means for individually moving said platen members toward and away from the circumference of said printing wheel, an impression recording tape intermediate 30 said wheel and said platen members, and means connected to said platen moving means whereby the quotations are recorded in one row and the symbols representing the stock are recorded in a second row offset from said 35 first row.

5. In a stock quotation system, a facsimile telegraph system having means for reducing the time required and record symbols representing the stock in one row and the quotations in another

row offset from said first row with at least as narrow a frequency band as required to transmit and record both types of symbols in a single row which comprises a receiving mechanism having two independent platens one of which records the stock symbols and the other the quotation, independent means for controlling said platens, and circuit instrumentalities connecting said controlling means to said system whereby said platens are actuated in accordance with received im- 10 pulses representing said symbols.

6. A facsimile telegraph system comprising a transmitter having means for translating symbols into positive telegraph impulses and other means for translating symbols into negative tele- 15 graph impulses, a receiver having means for translating negative telegraph impulses into the corresponding symbols and for recording said symbols in a straight line, said receiver having other means for translating positive impulses and 20 recording the corresponding symbols in a second row offset from said first row of symbols, and a telegraph transmission channel connecting said transmitter and said receiver.

7. A facsimile telegraph receiver comprising a 25 rotatable printing wheel provided with a plurality of spiral printing edges, a platen member adjacent thereto, means for actuating said platen in response to positive telegraph impulses, a second platen adjacent said printing wheel, means 30 for actuating said second platen in response to negative telegraph impulses, a tape and ink ribbon between said printing edges and said platens whereby said positive impulses are recorded on one portion of said tape and said negative im- 35 pulses are recorded on another portion of said tape.
